CONTROL SYSTEM

Willis H. Gille, St. Paul, Minn., assignor to Minneapolis-Honeywell Regulator Company, Minneapolis, Minn., a corporation of Delaware

Application September 24, 1934, Serial No. 745,374

6 Claims. (Cl. 236—44)

This invention relates to control mechanisms in which small and delicate changes in a condition are amplified to operate devices requiring a relatively stronger force and has particular 5 utility in humidity control devices wherein the changes in the condition are small and delicate and not sufficient to operate the humidity control device directly.

An object of this invention is to provide a 10 more sensitive control mechanism wherein small and delicate changes in a condition acting thereon which are insufficient to operate a control device directly are amplified to operate said control device.

15 Another object of this invention is to provide a control mechanism wherein an off and on control is provided at the command of a small change in resistance of an active element of the variable resistance type.

20 A further object is to provide a control mechanism wherein voltage changes and ambient temperature changes are compensated to nullify their effect.

A still further object is to provide a control 25 mechanism wherein the control point may be adjusted from a remote position.

More specifically, another object is to provide a 30 humidity control system wherein small and delicate changes in resistance of a humidity responsive variable resistance are amplified to provide an off and on control for a mechanism to control the humidity.

Other objects and advantages will become 35 apparent to those skilled in the art by reference to the accompanying specification and drawing in which there is shown a diagrammatic view of my control system, preferably applied to a humidity control.

The control system is of general utility and 40 may be used in connection with practically any system and may be responsive to practically any condition but for purposes of illustration and not for limitation it is shown as applied to a humidity control wherein 10 is a water pipe delivering a 45 spray of water to the space, the humidity of which is to be controlled. Located in the pipe 10 is an open and shut valve 11 operated from full open position to full closed position and vice versa by a double solenoid which valve and solenoid may take the form disclosed in the patent to George D. Bower No. 1,861,046, filed May 24th, 1928, and patented May 31st, 1932.

The energy for operating the double solenoid 12 is obtained from line wires 13 and 14, line 55 wire 13 being made flexible as at 15 and being

soldered to a contact arm 16. Line wire 14 extends directly to the double solenoid. The contact arm 16 is adapted to selectively engage a contact 17 or a contact 18 which contacts are connected by wires 19 and 20 respectively to the 5 double solenoid 12.

When the contact arm 16 engages the contact 17, the double solenoid 12 is energized to close the valve 11 and when the contact arm 16 engages the contact 18, the double solenoid 12 is 10 energized to open the valve 11.

The contact arm 16 is operated by a double heat responsive device which consists of a bimetallic arm 24 secured at one end to a support 25 and a second bimetallic arm 22 secured at one 15 end thereof to the other end of the first bimetallic arm 24 by means of a pin 23. The lower end of the bimetallic arm 22 is connected to the contact arm 16. As the bimetallic element 24 is heated, it being secured to the support 25, the 20 element will bend or flex in a counter-clockwise direction thereby tending to move the contact arm 16 towards the contact 17. When the bimetallic element 22, being secured at its upper 25 end to the pin 23, is heated, it bends or flexes in a clockwise direction, tending to move the contact arm 16 towards the contact 17. It will be noted at this point that the elements 22 and 24 when heated operate in opposite directions 30 so that ambient changes in temperature of the surrounding atmosphere have no effect upon this portion of the instrument.

The bimetallic heat responsive element 22 is heated by a heating element 27 while the bimetallic heat responsive element 24 is heated by a heating element 28. These heating elements 27 and 28 obtain their energy from line wires 30 and 31 connected to the primary 33 of a step down transformer 32. The secondary 34 of the transformer 32 is connected by means of a wire 40 35 to one end of the heating element 28. The other end of the heating element 28 is connected by a wire 36 to an adjustable contact 37 operating on and contacting a resistance coil 38. This resistance coil 38 is connected by a wire 39 to a 45 wire 40 which in turn is connected to the other side of the secondary 34.

43 designates a variable resistance that may be of any type and which may be responsive to changes in any condition, preferably changes in 50 relative humidity, and it is herein shown as a humidity responsive variable resistance of the type shown and described in the patent to W. R. Starkins No. 1,694,107 filed March 24th, 1926 and patented December 4th, 1928. Such a variable 55

resistance consists of a wire 41 and a wire 42 each wire being insulated by cotton and wrapped closely together in the form of a coil. One wire 41 is connected to the wire 40 which in turn is connected to the secondary 34 of transformer 32. The other wire 42 of the variable resistance is connected by a wire 44 to one end of the heating element 27 while the other end of the heating element 27 is connected by a wire 45 to that end of heating element 28 which is connected to the wire 35.

The resistance 43 is varied by moisture permeating the cotton insulation of the wires 41 and 42 so that greater moisture lowers the resistance between wires 41 and 42 and less moisture increases the resistance therebetween the amount of resistance varying exponentially with respect to the vapor content or relative humidity of the atmosphere in which the device 43 is placed.

20 The circuit for operating the heat responsive element 24 is completed through the secondary 34 of the transformer 32, wire 35, heating element 28, wire 36, adjustable contact 37, resistance coil 38, wire 39 and wire 40.

25 The circuit for operating the heat responsive element 22 is completed through secondary 34, wire 35, wire 45, heating element 27, wire 44, conduction through the insulating means between wires 41 and 42 of the variable resistance 43, and the wire 40.

30 The adjustable resistance 38 determines the amount of heat given off by the heating element 28 and may be located at a point remote from the rest of the structure. By increasing the resistance 38, the amount of heat given off by the heating element 28 is reduced and by decreasing the resistance 38, the amount of heat given off by the heating element 28 is increased. For a given setting of the resistance 38, the heat given off by the heating element 28 will be substantially constant except for slight changes in line voltage thereby urging the contact arm 16 towards the contact 18 with a substantially constant force.

35 The heat given off by the heating element 27 is inversely proportional, in an exponential manner, to the amount of resistance in the resistance 43. As the humidity increases, the resistance of the variable resistance 43 decreases and permits heating element 27 to give off more heat to the 40 heat responsive element 22 to tend to urge the contact arm 16 towards the contact 17.

45 Due to the fact that the heating elements 27 and 28 cause the heat responsive elements 22 and 24 respectively to operate in opposite directions, and since both heating elements 27 and 28 receive 50 their energy from a common source, the lines 38 and 39, any fluctuations in the line voltage are compensated and nullified.

55 Assume that the parts are in equilibrium and are in the position shown in the drawing, heating element 28 tends to urge the contact arm 16 towards the contact 18 and heating element 27 tends to urge the contact arm 16 towards the contact 17. When the humidity decreases, the 60 resistance in the variable resistance 43 increases and causes the heat given off by the heating element 27 to decrease whereby the contact arm 16 will engage the contact 18 to energize the double solenoid 12 to open the valve which 65 supplies more water to the atmosphere and brings the humidity up to normal and allows the parts to resume their equilibrium positions as shown in the drawing. Assume that the humidity increases, the resistance 43 decreases, allowing the 70 heating element 27 to develop more heat to flex 75

the heat responsive element 22 which causes contact arm 16 to engage contact 17 to energize the double solenoid 12 to close the valve 11 to decrease the amount of water vapor in the air and bring the parts back to equilibrium again as shown in the drawing.

5 From the above, it is seen that I have provided a more sensitive control mechanism wherein small and delicate changes in conditions acting thereon which are insufficient to operate a control device directly are amplified to operate said control device.

10 While one embodiment of this invention has been shown and described, it is obvious that many modifications may be apparent to one skilled in the art and consequently, this invention is to be limited only by the scope of the appended claims.

I claim:

1. In a control system of the character described, a variable resistance responsive to changes in humidity, a solenoid operated valve mechanism to control the humidity, an off and on switching mechanism, a circuit connecting said off and on switching mechanism and said solenoid operated valve mechanism to open and close said valve mechanism in response to said switching mechanism, means to operate said switching mechanism according to changes in resistance in said humidity responsive variable resistance comprising a heat responsive element secured at one end and acting in one direction, a second heat responsive element secured at one end to the other end of said first heat responsive element and at the other end to said switching mechanism and acting in the opposite direction whereby ambient temperature changes are compensated, a source of energy, a heating element controlling said first heat responsive element, a circuit connecting said source and said heating element to constantly urge said switching mechanism in one direction, a second heating element controlling said second heat responsive element and a second circuit connecting said source, said humidity responsive variable resistance and said second heating element to urge said switching mechanism in the other direction according to changes in humidity acting on said variable resistance whereby both of said heating elements are arranged to compensate for voltage changes in said source and an adjustable resistance in said first circuit to adjust the heating effect of said first heating element to make said control system responsive to greater or less conditions of humidity.

2. In a control system of the character described, a variable resistance responsive to changes in humidity, a solenoid operated valve mechanism to control the humidity, an off and on switching mechanism, a circuit connecting said off and on switching mechanism and said solenoid operated valve mechanism to open and close said valve mechanism in response to said switching mechanism and means to operate said switching mechanism according to changes in resistance in said humidity responsive variable resistance comprising a heat responsive element secured at one end and acting in one direction, a second heat responsive element secured at one end to the other end of said first heat responsive element and at the other end to said switching mechanism and acting in the opposite direction whereby ambient temperature changes are compensated, a source of energy, a heating element controlling said first heat responsive element, a circuit connecting said source and said heating

element to constantly urge said switching mechanism in one direction, a second heating element controlling said second heat responsive element and a second circuit connecting said source, 5 said humidity responsive variable resistance and said second heating element to urge said switching mechanism in the other direction according to changes in humidity acting on said variable resistance whereby both of said heating elements 10 are arranged to compensate for voltage changes in said source.

3. In a control system, a variable resistance responsive to changes in a condition, an electrically operated control mechanism to control said 15 condition, an off and on switching mechanism, a circuit connecting said switching mechanism and said electrically operated control mechanism to operate said control mechanism in response to said switching mechanism, means to operate 20 said switching mechanism according to changes of resistance in said variable resistance comprising a heat responsive element secured at one end and acting in one direction, a second heat responsive element secured at one end to the other 25 end of said first heat responsive element and at the other end to said switching mechanism and acting in the opposite direction whereby ambient temperature changes are compensated, a source of energy, a heating element controlling said first 30 heat responsive element, a circuit connecting said source and said heating element to constantly urge said switching mechanism in one direction, a second heating element controlling said second heat responsive element and a second 35 circuit connecting said source, said second heating element and said variable resistance to urge said switching mechanism in the other direction according to changes in the condition acting on said variable resistance whereby both 40 of said heating elements are arranged to compensate for voltage changes in said source and an adjustable resistance in said first circuit to adjust the heating effect of said first heating element to make said control system responsive to 45 greater or less changes in the condition.

4. In a control system, a variable resistance responsive to changes in a condition, an electrically operated control mechanism to control said condition, an off and on switching mechanism, 50 a circuit connecting said switching mechanism and said electrically operated control mechanism to operate said control mechanism in response to said switching mechanism, and means to operate said switching mechanism according to changes 55 of resistance in said variable resistance comprising a heat responsive element secured at one end and acting in one direction, a second heat responsive element secured at one end to the other

end of said first heat responsive element and at the other end to said switching mechanism and acting in the opposite direction whereby ambient temperature changes are compensated, a source of energy, a heating element controlling said first heat responsive element, a circuit connecting said source and said heating element to constantly urge said switching mechanism in one direction, a second heating element controlling 5 said second heat responsive element and a second circuit connecting said source, said second heating element and said variable resistance to urge said switching mechanism in the other direction according to changes in the condition 10 acting on said variable resistance whereby both 15 of said heating elements are arranged to compensate for voltage changes.

5. In a control system, the combination of, a variable resistance responsive to changes in a condition, a mechanism to be operated, means to 20 operate said mechanism according to changes of resistance in said variable resistance comprising a heat responsive element secured at one end and acting in one direction, a second heat responsive element secured at one end to the other end of said first heat responsive element and at the other end to said mechanism and acting in the opposite direction whereby ambient temperatures are compensated, a source of energy, a heating 25 element controlling said first heat responsive element, a heating element controlling said second heat responsive element, and connections between said source, said variable resistance and 30 said heating elements whereby said mechanism is moved in accordance with changes in the condition 35 varying the resistance.

6. In a control system, the combination of, a variable resistance, a mechanism to be operated, means to operate said mechanism according to 40 changes of resistance in said variable resistance comprising a heat responsive element secured at one end and acting in one direction, a second heat responsive element secured at one end to the other end of said first heat responsive element and at the other end to said mechanism 45 and acting in the opposite direction whereby ambient temperatures are compensated, a source of energy, a heating element controlling said first heat responsive element, a circuit connecting said source and said heating element to urge 50 said mechanism in one direction, a second heating element controlling said second heat responsive element, and a second circuit connecting said source, said second heating element and said 55 variable resistance to urge said mechanism in the other direction according to changes in resistance of said variable resistance.

WILLIS H. GILLE.
